[57] CLAIM

The ornamental design for a combined bottle and cap or similar article, substantially as shown and described.

DESCRIPTION

FIG. 1 is a front elevational view of a combined bottle and cap or similar article showing our new design;

FIG. 2 is a side elevational view thereof with a portion broken away for convenience of illustration;

FIG. 3 is a cross sectional view taken along the lines 3—3, of FIG. 1;

FIG. 4 is a cross sectional view taken along the lines 4—4, of FIG. 1;

FIG. 5 is a cross sectional view taken along the lines 5—5, of FIG. 1;

FIG. 6 is a cross sectional view taken along the lines 6—6, of FIG. 1; and

FIG. 7 is a cross-sectional view taken along the lines 7—7 of FIG. 2.

The two circular areas on the top sphere represent internal bubbles.
